UNITED STATES PATENT OFFICE.

THOMAS SUGDEN, OF LONDON, AND ALFRED EDWARD FIELDING, OF MANCHESTER,
ENGLAND.

STEAM-SUPERHEATER.

1,318,185.

Specification of Letters Patent.

Patented Oct. 7, 1919.

Application filed December 17, 1915. Serial No. 67,463.

To all whom it may concern:

Be it known that we, THOMAS SUGDEN and ALFRED EDWARD FIELDING, subjects of the King of Great Britain, and residents, respectively, of London, England, and Manchester, Lancashire, England, have invented new and useful Improvements in Steam-Superheaters, of which the following is a specification.

10 This invention relates to steam superheaters applicable to locomotive, road traction, marine, land and portable types of steam generators and provides a novel construction and arrangement of steam chambers or headers, flue tubes and superheater tubes whereby the following advantages are secured:—viz: All the superheater elements are alike and interchangeable whereby the construction is simplified and the minimum 15 number of spare elements need be kept; no special tools are required for expanding and drifting; only one or two small parts are required to be taken down in order to permit of removing an element; any element 20 can be removed without interfering with the other elements; elements can be replaced and used again without necessitating re-bending of the tubes; and easy accessibility of the elements and smoke tubes for cleaning purposes is insured as well as ready facility for plugging a tube in case of failure.

In the accompanying drawings we have shown by way of example the application of our invention to a locomotive boiler.

35 Figure 1 is a vertical longitudinal section through a locomotive smoke box showing as much as is necessary of the boiler and superheater.

40 Fig. 2 is a vertical transverse section through one half of the smoke box and superheater header, the other half being represented in elevation.

45 Fig. 3 is a longitudinal section through a portion of a superheater of slightly modified construction.

Fig. 4 is a section on the line Y, Y, Fig. 3 looking upward.

Fig. 5 is a view of a device for plugging the superheater tubes when required.

50 Fig. 6 is a section illustrating a modified method of connecting the superheater tubes to the header.

Fig. 7 is a view of a device suitable for plugging the superheater tube in Fig. 6.

Fig. 8 is a partial transverse sectional view of a further modified form of header.

Fig. 9 is a sectional elevation, and

Fig. 10 a sectional plan illustrating still another form of header, and

Fig. 11 is a sectional elevation of another modification.

Figs. 3 to 11 are drawn to a larger scale than Figs. 1 and 2.

Like letters of reference denote corresponding parts in the several figures.

The header A is shown extending across the upper part of the smoke box B and down each side of the smoke box. That is to say, the header has two dependent legs, but it may have only one, or in some cases as in 70 marine or other large boilers it may have more than two legs. The header is divided into two chambers by a partition C and one of these chambers communicates with the boiler by a pipe D while the other communicates with the steam main by pipes E. The superheater tubes F forming the elements of the superheater are secured to the rear walls of boxes G which are arranged in pairs, one box of each pair communicating 80 with one chamber of the header, and the other with the other chamber of the header. The boxes G are however not arranged in line with the corresponding flue tubes H but are displaced upwardly, downwardly, or 85 laterally with reference thereto, and consequently the projecting ends of the superheater tubes are necessarily formed with a double bend or crank; as seen in Fig. 1. When it is required to withdraw an element, the ends of 90 the superheater tubes are detached from the header, the element is pushed rearwardly some distance and then turned through a suitable angle which causes the cranked ends to move clear of the header whereupon the 95 element can be withdrawn. The reverse movements are made when inserting an element. The disposition of the boxes G of the header is such that any one element can be turned in its smoke tube H as above described without bringing the cranked ends into contact with the adjacent elements, and to allow of employing the maximum number of elements a zigzag arrangement of the boxes G as indicated in Fig. 2 is preferably 100 adopted. The front ends of the boxes G are fitted with removable screw plugs or caps J to allow of obtaining access to the super-

heater tubes for attaching and detaching purposes or for plugging them when required.

In Fig. 3 we have shown a slightly modified construction of header in which the boxes G are shorter than those shown in Fig. 1 thus affording greater facility in the use of the attaching and detaching tools. The sectional underside plan Fig. 4 illustrates 10 the shape of the boxes G very clearly, and also the openings K, leading into the chambers of the header.

Should one of the superheater tubes become damaged, it can be plugged by removing the screw caps J and replacing same by screw plugs L shown in Fig. 5 which have a piston like inner end M suitably packed, e. g. with asbestos and adapted to fit tightly in the superheater tubes.

20 In Figs. 3 and 4 the superheater tubes are shown secured to the header by expanding the ends of the tubes.

In Fig. 6 another method of attachment is shown. This attachment is effected by a 25 separate machined tubular connecting piece N screwed on the end of the superheater tube. This connecting piece is formed with a shoulder at O and is passed right through the box G and secured by a box nut P. Communication between the box G and the superheater tube is made through a slotted opening R. The rod Q for plugging when required this type of connection is shown in Fig. 7.

35 Fig. 8 illustrates a slight modification of the shape of the boxes G which admits of arranging the flue tubes H somewhat closer together while affording all the necessary space for attaching the superheater tubes. In other respects the header is similar to that shown in Fig. 2.

It will be obvious that a modified form of 45 header may be used in which the boxes G are dispensed with, the superheater tubes being passed right through the header from back to front and being secured by nuts, or said tubes being secured to separate sleeves or connections N which pass through the header as shown in Figs. 9 and 10 and are

secured by box nuts P. Ports or passages 50 R are formed in the sleeves or connections N so that one leg of the superheater element communicates with one chamber of the header, and the other leg with the other chamber of the header.

55 A further modification is shown in Fig. 11 in which the superheater tubes F are expanded into the header, and the sleeve N is screwed through the front wall of the header and passes tightly through the center wall C 60 and abuts against the back wall of the header. The sleeve passes over the expanded end of the superheater tube. The outer end of the sleeve N in this modification is shown closed, and is covered by a 65 box nut P. The sleeve leading from one end of the superheater element has a port at R to communicate with one chamber of the header, and the sleeve from the other end of the element is similarly slotted to 70 communicate with the other chamber of the header.

What we claim is:—

In a steam superheater for steam generators, and in combination, a header, superheater tubes having threaded ends, a tubular connecting member for each tube removably secured to and extended through said header and having one end to threadedly connect with the threaded end of the tube, 75 said connecting member having a passage therein connecting the interior thereof with the interior of said header, and a removable plug for said connecting member adapted to close the other end thereof and having an extension for closing the passage of fluid 80 through said superheater tube.

85 THOMAS SUGDEN.

ALFRED EDWARD FIELDING.

Witnesses to the signature of the said Thomas Sugden:

CONRAD K. FALKENSTEIN,
GEO. A. RAFFLES.

Witnesses to the signature of the said Alfred Edward Fielding:

EDWARD L. BOUTILLIER,
JOHN CROMPTON.
